COALING GATE FOR LOCOMOTIVES

Werner Dietrich, Chicago, Ill., assignor to Roberts and Schaefer Company, Chicago, Ill., a corporation of Illinois

Application November 16, 1935, Serial No. 50,073

13 Claims. (Cl. 193—21)

My invention relates to improvements in coal chutes. It has for one object to provide a new and improved form of coal chute particularly for use in connection with locomotive fueling stations wherein the gate which controls the flow of coal will not jam, will not permit unauthorized or unintended leakage of coal, will insure a uniform flow of coal from the bin while preventing skimming or control of the character of coal by chute manipulation. Other objects will appear from time to time throughout the specification and claims.

My invention is illustrated more or less diagrammatically in the accompanying drawings, 15 wherein—

Figure 1 is a side elevation in part section; Figure 2 is a section along the line 2—2 of Figure 1;

Figure 3 is a side elevation on an enlarged scale of the gate and associated parts;

Figure 4 is a section through the gate and associated parts parallel to the view shown in Figure 3;

Figure 5 is a section along the line 5—5 of Figure 3;

Figure 6 is a front elevation of the gate in the closed position;

Figure 7 is a section along the line 7—7 of Figure 3.

Like parts are indicated by like characters throughout the specification and drawings.

1 is a coal bin having an inclined bottom wall 2, a vertical front wall 3, there being an aperture or port 4 in the front wall immediately adjacent the lower extremity of the inclined bin. This aperture 4 is encircled by an angle flange 5 to which is bolted a fixed gate chute 6 which is rectangular in cross section, the lower floor of which is in general alignment with the floor 2. 10 7, 7 are brackets on the upper wall of the fixed chute. 8 is a rock shaft rotatable in those brackets. 9, 9 are sleeves bolted to the opposed ends of the rock shafts having lugs 10 to which are bolted control levers 11 from which depend 15 downwardly operating rods 12, from which the engineer or fireman in the tender may open or close the gate. Extending downwardly along opposed sides of the fixed chute from and rigidly mounted on the rock shaft 8 are rock arms 13. A lower gate link 14 is pivoted to each rock arm 13 and an upper gate link 15 slotted at 16 is engaged by the pivot pin 17 that joins the three links. The gate is a two part gate, the upper part comprising an arcuate member 18 having 20 inwardly turned flanges at each end pivoted at

19 on the side walls of the fixed chute. The link 15 is pivoted to a lug 20 on each of said inturned ends so that the link 15 causes rotary movement of the upper gate portion 18 about its pivot point. The upper gate arcuate portion 18 has a straight cutting edge extending clear across the chute. The lower gate member comprises two superposed arcuate gate sections 21, 22, section 21 being reinforced by 22 and both being supported on a stirrup 23 having stirrup arms also pivoted at 16 15. The link 14 pivoted to a lug 24 causes operation of this stirrup member. Reference to Figure 6 shows that the undercut portion does not have a straight cutting lip but tapers upwardly to a point at the center.

Figure 3 shows the parts in the closed position. Figure 4 shows the parts in the open position. A counter clockwise rotation of the rock shaft 8 first takes place without movement of the gate 18 because the pin 17 slides in the slot 16 and cushions the opening movement of the lower gate section. Later on as the excursion proceeds to the position shown in Figure 4 both gates are opened. On the return or closing movement clockwise direction of the rock shaft 8 immediately causes a forward or closing movement of the lower gate but the closing movement of the upper gate does not start until the pin 17 has returned from the position of Figure 4 in the right hand end of the slot to the position of Figure 3 in the left hand end of the slot.

The result of this is that in order to open the gate, the operator must manipulate the rock shaft to first start the withdrawal of the lower pointed gate member and then to finish with the completion of its withdrawal and the opening of the upper straight edged gate portion. This results in a full flow of coal. As the gate closes, the upper gate portion remains at rest until the pointed gate portion has come partially into play tending to divide the flow of coal and tending as the two gates come together to gradually restrict the passage up to a point where the pointed gate is immediately adjacent the upper gate when coal flows through two passages, one at either side of the chute. Therefore coal movement is entirely stopped. This arrangement insures that a uniform flow of coal will take place.

Depending downwardly from the pivot pins 19 on the fixed chute is a yoke 25 which yoke extends across beneath the fixed chute. 26 is an adjustable chute pivoted on the yoke. This adjustable chute extends upwardly behind and above the lower extremity of the fixed chute and has at its end a boot 27 adapted to catch and 50 55

guide the coal. 28 is a ring associated with the boot which may be grasped by a hook 29 in the hands of the operator to pull the adjustable chute down from the position shown in dotted lines 5 in Figure 1 to the position shown in full lines. 30 is a bail to which is fastened a holding rope 31 which extends up to any suitable counter-balance. Figure 2 shows the angle of movement possible for this adjustable chute whereby the coal may be properly positioned on the 10 tender of the locomotive.

32 is a flange extending across the upper outside wall of the chute adapted to limit the upward movement of the gate 18. Welded to the 15 flange 32 and extending downwardly on both sides of the chute are channelled bearing members 33 for the pivot pins 19.

I claim:

1. In combination, a fixed downwardly inclined chute, two gate members pivoted on a horizontal axis on the chute, adapted to move toward and from one another across the open end of the chute, the upper member having a cut off edge parallel with and the lower member having 25 a cut off edge inclined to the axis of rotation.

2. In combination, a fixed downwardly inclined chute, two gate members pivoted on a horizontal axis on the chute, adapted to move toward and from one another across the open 30 end of the chute, the upper member having a straight cut off edge, the lower member having a cut off edge which is inclined upwardly from each end toward the middle.

3. In combination, a fixed downwardly inclined chute, two gate members pivoted on a horizontal axis on the chute, adapted to move toward and from one another across the open end of the chute, the upper member having a straight cut off edge, the lower member having 35 an inclined cut off edge, means for rotating said gates comprising a rock shaft, rock levers depending therefrom, links each separately pivoted on the upper and lower gate and pivoted on the rock lever.

4. In combination, a fixed downwardly inclined chute, two gate members pivoted on a horizontal axis on the chute, adapted to move toward and from one another across the open 50 end of the chute, the upper member having a straight cut off edge, the lower member having a cut off edge which is inclined upwardly from each end toward the middle, means for rotating said gates comprising a rock shaft, rock levers depending therefrom, links each separately pivoted on the upper and lower gate and pivoted on the 55 rock lever.

5. In combination, a fixed downwardly inclined chute, two gate members pivoted on a horizontal axis on the chute, adapted to move toward and 60 from one another across the open end of the chute, the upper member having a straight cut off edge, the lower member having an inclined cut off edge, means for rotating said gates comprising a rock shaft, rock levers depending therefrom, links each separately pivoted on the upper and lower gate and pivoted on the 65 rock lever, one of said links having a slot whereby movement of the rock lever and the other link takes place through a limited excursion without movement of the slotted link.

6. In combination, a fixed downwardly inclined chute, two gate members pivoted on a horizontal axis on the chute, adapted to move toward and from one another across the open 70 end of the chute, the upper member having a 75

straight cut off edge, the lower member having a cut off edge which is inclined upwardly from each end toward the middle, means for rotating said gates comprising a rock shaft, rock levers depending therefrom, links each separately pivoted on the upper and lower gate and pivoted on the rock lever, one of said links having a slot whereby movement of the rock lever and the other link takes place through a limited excursion without movement of the slotted link. 10

7. In combination, a fixed downwardly inclined chute, two gate members pivoted on a horizontal axis on the chute, adapted to move toward and from one another across the open 15 end of the chute, the upper member having a straight cut off edge, the lower member having an inclined cut off edge, means for rotating said gates comprising a rock shaft, rock levers depending therefrom, links each separately pivoted on the upper and lower gate and pivoted on the 20 rock lever, one of said links having a slot whereby movement of the rock lever and the other link takes place through a limited excursion without movement of the slotted link, the slotted link being associated with the upper gate. 25

8. In combination, a fixed downwardly inclined chute, two gate members pivoted on a horizontal axis on the chute, adapted to move toward and from one another across the open 30 end of the chute, the upper member having a straight cut off edge, the lower member having a cut off edge which is inclined upwardly from each end toward the middle, means for rotating said gates comprising a rock shaft, rock levers depending therefrom, links each separately pivoted on the upper and lower gate and pivoted on the rock lever, one of said links having a slot whereby movement 35 of the rock lever and the other link takes place through a limited excursion without movement of the slotted link, the slotted link being associated with the upper gate. 40

9. In combination, a fixed downwardly inclined chute, two gate members pivoted on a horizontal axis on the chute, adapted to move toward and from one another across the open end of the chute, the upper member having a straight cut off edge, the lower member having a cut off edge which is inclined upwardly from each end toward the middle, the lower gate comprising two arcuate structural sheets, a stirrup upon which they are both mounted, the stirrup having at each end 45 upwardly extending portions pivoted on the chute, the two sheets being in engagement adjacent their outer edges whereby one reinforces the other. 50

10. In combination, a fixed chute, a two-part gate pivoted on and adapted to close the chute including upper and lower gate members, means for rotating them toward and from one another, the upper member having a straight cut off edge, the lower member having a cut off edge bounded by two upwardly inclined lines. 60

11. In combination, a fixed chute, a two-part gate pivoted on and adapted to close the chute including upper and lower gate members, means for rotating them toward and from one another, the upper member having a straight cut off edge, the lower member having a cut off edge bounded by two upwardly inclined lines, so that as the gates approach one another, the lower gate comes 65 into alignment with the upper at the center before it does at the sides. 70

12. In combination, a fixed downwardly inclined chute, two gate members pivoted on a horizontal axis on the chute adapted to move 75

5 toward and from one another across and immediately at the open end of the chute, a single operating means for rotating said gates, a link connection between said means and the gates, including a pin and a slot adapted to cause successive operation of the two gates in response to the manipulation of the opening means.

10 13. In combination, a fixed downwardly inclined chute, two gate members pivoted on a horizontal axis on the chute adapted to move toward and from one another across and imme-

diately at the open end of the chute, a single operating means for rotating said gates, a link connection between said means and the gates, including a pin and a slot adapted to cause successive operation of the two gates in response to the manipulation of the opening means, said connecting means being adapted to cause a reversal of the time of opening of one gate with respect to the other when they are opened and when they are closed. 5

10

WERNER DIETRICH.
